UNITED STATES PATENT OFFICE

BYRON C. LEAVITT, OF DUXBURY, MASSACHUSETTS

INVALID LIFTER

Application filed May 15, 1930. Serial No. 452,662.

This invention relates to an invalid lifter which is adapted to support, convey and in general afford convenient mobility to the body of an invalid, whether weakened from sickness, paralyzed or otherwise more or less helpless.

This invention provides a support for the invalid which is so arranged in relation to suitable running gear that the invalid may be readily lifted from a bed or the like and transported to any desired location, for example being held in or over a bath tub, the apparatus permitting the weight of the invalid readily to be supported when thus held in an overhanging position in relation to a bed or bath tub. Thus the running gear is provided with a portion which may run under the bed or a bath tub, and the invalid supporting portion of the device is so arranged that the invalid may be swung about a substantially vertical support which is carried by the running gear.

The present invention provides particularly convenient and readily operable and controllable means for lifting and lowering the invalid support or for locking the same at any desired height. The invalid support is so connected by a movable brace with the main upright of the device that undesirable swaying or swinging of the invalid is avoided. Preferably the main upright is continued in a curved upper portion which is provided with a plurality of pulleys, these pulleys being arranged to permit the ready movement of a cable over the same, the end of this cable being connected to the invalid support itself. The running gear may be readily adjustable to permit the base of the device to have a relatively great width, thereby aiding stability when desired or to permit the base to be made narrower to permit ready passage through narrow doors, between articles of furniture or the like.

In general the objects of this invention are to provide a simple and sturdy invalid lifter which is adapted to a wide variety of uses and conditions, which may permit the convenient lifting or movement of the invalid by one person, and which is adapted to support the

invalid in a substantially sitting position, although the invalid may be quite helpless.

In the accompanying drawings:

Fig. 1 is an elevational view of the device, certain parts being broken away for clarity of illustration;

Fig. 2 is a side elevation of the invalid support proper showing the relationship of the parts when the invalid is being supported;

Fig. 3 is a section on line 3—3 of Fig. 1;

Fig. 4 is a broken elevational view of the means for lifting or lowering the invalid or for holding him in desired elevation;

Fig. 5 is a section on line 5—5 of Fig. 1;

Fig. 6 is a section on line 6—6 of Fig. 4; and

Fig. 7 is a section indicated by line 7—7 of Fig. 5.

In the accompanying drawings, the numeral 1 designates the frame of the running gear, which may be substantially cross-shaped, being provided with a tubular longitudinal frame member 2 and with a transverse bracket-like frame portion 3 secured to the member 2 somewhat nearer its rear end and providing a cup-like support 5 for the main upright 6 adjoining the point of intersection of members 2 and 3. Suitable swivel rollers 7 are disposed at the ends of the member 2 and the ends of the cross member 3, the roller at the front of the member 2 being arranged to swivel about a substantially vertical pivot 9, and the roller at the rear of the member 2 having its swivel axis offset in relation to its axis of rotation to provide a caster effect. The rollers at the ends of the member 3 are similarly connected to arms 10 that are provided with forked ends 11 pivotally connected to ends of arm 3. Suitable king bolts 12 secure the arms 10 to the ends of the frame member 3, these king bolts being provided with nuts 13 having outstanding handles 14 that permit the loosening and tightening of the king bolts. When the nut upon one of the king bolts is loosened, the arm 10 may be swung about the bolt so that the effective width of the running gear may be varied;

thus as shown in Fig. 5 the arm 10 may be swung from the full to the dotted line position to provide a greater effective width for

the base or running gear of the invalid lifter. Obviously when the arm 10 is moved to the desired adjusted position the handle 14 is again actuated to tighten the retaining nut 5 and to hold the arm in its new position.

The cup-like element 5 contains an inner sleeve 5^a which acts as a spacer for anti-friction bearings 16, which in turn support the upright 6, thus the upright is swivelly 10 mounted upon the anti-friction bearings. A suitable diagonal brace 20 extends upwardly from the rear of frame member 2 to a collar 21 secured to the intermediate part of the upright 6. Above this collar the upright is 15 provided with a cup-like portion 21 which is adapted to telescope with the lower end of an upper section 6^a of the upright, a retaining pin 23 extending through registering openings in the lower end of the member 6^a 20 and the cup-like extension 21 of the member 6 to hold these parts in their normally assembled position. It is thus evident that the upright is made in two parts and may readily be disassembled for more convenient shippage 25 or storage. The upper part of the upright portion 6^a is provided with a gradual curvature so that its overhanging end 25 is disposed substantially horizontally. A plurality of grooved rollers 29 are pivotally supported 30 by brackets 30 secured to the curved part of the upright. A cable 31, which may be connected to suitable control mechanism 32, engages the grooves of these rollers, and extends downwardly at the end of the overhanging portion 25 of the member 6^a and has an eye 33 which receives a hook 34 forming a part of the invalid support 35.

This invalid support 35 comprises a cross member 36 supported by the hook 34 and is 40 adapted to support any suitable flexible or rigid device for holding and supporting the invalid. Figs. 1 and 2 illustrate the preferred form of such a supporting device which comprises a canvas strip or sheet 50 which is adapted to support the weight of the invalid and which is provided with U-shaped extensions or straps 51, each of which are engaged between two upwardly 45 extending elements or hooks 52 at the ends 50 of the cross member 36. In many cases it is desirable to support the shoulders of the invalid and accordingly for this purpose I provide a shoulder strap 55, which may be conveniently formed of canvas and which 55 is connected to the ends of the cross member 36 by cables 56, which may have suitable means for adjusting their effective lengths. It is thus evident that this arrangement permits the main portion of the invalid's 60 weight to be supported by the member 50, while the upper part of the back or shoulders may be supported by the strap 55, the cables 56 extending under the arms of the invalid and the parts then occupying substantially 65 the position shown in Fig. 2.

In order to avoid undesirable swinging of the support 35 about the cable 33 a guide rod 60 is connected to the end of the cross member 36 and to the upright 6. For this purpose a substantially horizontal pivot pin 61 extends through a fork 62 at the upper end of the rod 60 and pivotally connects the same to the cross member 36, while the lower end of this rod has a forked end 64 that is connected by a horizontal pivot 65 with an ear 66 extending from a plate 67, Fig. 3. This plate is secured between the two segmentally shaped blocks 68 which are slidably mounted within the tubular upright 6. A vertical slot 69 is provided to permit the ready vertical movement of the ear 66. It is thus evident that the upright 6 may rotate about the bearing 16 but that the cross member 36 of support 35 is always maintained in a substantially radial position in relation to the swivel axis of the upright, accordingly undesirable twisting or swinging of the support 35 is prevented; furthermore the forked connections at the end of the brace 60 prevent swaying of member 65 and permits the satisfactory employment of a single cable to support the invalid.

One important aspect of the present invention comprises the means 32 permitting the ready lifting and lowering of the support 35. For this purpose a suitable housing or casing 70 is secured by bolts 71 to the upright 6. This casing carries a drum or windlass 72 to which the end of the cable 31 is connected and upon which the cable may be wound. The windlass 72 is provided with a shaft 73 supported by anti-friction bearings 74 in the casing 70. A gear 75 is also keyed to the shaft 73 and meshes with a pinion 76 upon a shaft 77 that is also supported by ball bearings in the casing, and is provided with an extension 78 that receives an operating crank 79. A toothed locking wheel 80 is also secured to the shaft 77 and is adapted to engage the end of a locking plunger 81. This plunger is vertically movable in a cylinder 82 and is provided with a head 83 that is urged downwardly by a coil spring 84 engaging a shoulder in sleeve 82. A transverse pin 85 is secured to the plunger and extends through slots 86 in the sleeve 82 to prevent rotation of the plunger. The upper end of the plunger is provided with a handle 89 and its lower end 83 is provided with a vertical surface 92 to engage the teeth of the ratchet wheel when the latter tends to move in the direction indicated by the curved arrow in Fig. 4, i. e. in response to a downward pull upon the depending end of cable 31. Thus the plunger 81 is effective in locking the support 35 against downward movement, except when it is lifted against the action of the spring 84 by means of the handle 89. Obviously under these conditions the invalid

can be lowered until the handle is released when the plunger 89 will instantly and automatically lock the ratchet wheel to prevent further downward movement of the support 35.

The plunger head 83 is provided with a beveled face 96 opposite the straight face 92 so that the plunger readily permits the movement of the ratchet wheel in a direction counter to that indicated by the curved arrow in Fig. 4. Accordingly the crank 79 may be operated to effect the lifting of the support 35 without necessity for releasing the plunger, while movement of the support 35 downwardly due to the weight of the invalid may be effected by releasing the plunger by means of the handle 89.

Under certain conditions it is desirable to provide additional means to prevent tipping of the device under the weight of the invalid and accordingly a foothold 100 is disposed diagonally between one portion of the frame member 3 and the rear of the machine, Fig. 5. Thus when the support 35 is swung to a position substantially such that the cross piece 36 is in the plane of the member 3 the operator's foot may be placed upon the member 100 to prevent tipping of the machine. Such an arrangement is particularly desirable, for example, when the invalid is to be supported over a built-in bath tub, which prevents a portion of the frame, such as the forward part of the member 2, from being located under the bath tub and accordingly substantially under the center of gravity of the weight supported by the upright 6.

It is evident that this apparatus permits convenient lifting and maneuvering of an invalid and that the lifting and lowering mechanism provides an easily operable means whereby a person of ordinary strength may lift and lower a comparatively heavy invalid. This lifting and lowering means is arranged so that lowering of the invalid may be instantly stopped by the plunger 81, while the gearing and crank 79 in conjunction with the anti-friction bearings permit the easy movement of the support 35 in the opposite direction.

The curved shape of the upper portion of the upright in conjunction with the arrangement of the grooved rollers prevents any liability of the cable binding and reduces friction losses. Swinging of the cross member 36 and support 35 about the cable is substantially prevented by the brace 60, while the entire support and upper portion of the upright may be swung about the anti-friction rollers 16, when desired. Obviously the arrangement of the arms 10 permits the convenient adjustment of the effective width of the device so that the running gear may ordinarily provide the maximum stability and yet be made to pass through a relatively narrow space such as a narrow door.

I claim:

1. An invalid lifter and conveyor comprising a running gear, invalid supporting means, an upright swivelly connected to the running gear to swing about a substantially vertical axis and having an overhanging portion, a movable cable having an end portion depending from said portion and connected to said means, and mechanism mounted on the upright and connected to the cable to vary the length of the depending cable end portion and the height of said supporting means, said supporting means including a transverse member and a body carrying element depending therefrom, the upright having a tubular portion with a vertical slot, means slidable in said tubular portion and a brace connected to said slidable means and guided by the slot, said brace being connected to the supporting means to prevent swinging of the same about the depending cable portion.

2. An invalid lifter and conveyor comprising running gear including a frame, invalid supporting means, an upright carried by the running gear and having an overhanging portion, a movable cable having an end portion depending from the upright and connected to said supporting means, mechanism mounted on the upright and connected to the cable to vary the length of the depending cable end portion and the height of said supporting means, the upright being swivelly mounted upon an anti-friction bearing carried by the frame of the running gear so that the supporting means may be swung about a substantially vertical axis, the frame having portions extending outwardly from said bearing, swinging arms pivotally mounted on the frame, rollers supported upon the outer ends of the arms, and means for frictionally locking the arms in any one of a multiplicity of positions to permit variation in the effective width of the running gear.

Signed by me at Boston, Massachusetts, this twelfth day of May, 1930.
